Thomas D. Linton.

UNITED STATES PATENT OFFICE.

DAVID N. MELVIN, OF LINOLEUMVILLE, NEW YORK.

DESIGN FOR A STEAM-ENGINE FRAME.

SPECIFICATION forming part of Design No. 14,411, dated November 13, 1883.

Application filed March 23, 1883. Term of patent 11 years.

To all whom it may concern:

Be it known that I, DAVID N. MELVIN, a subject of the Queen of Great Britain, residing at Linoleumville, Richmond county, in the State of New York, have invented and produced a new and original Design for Steam-Engine Frames, of which the following is a specification, reference being had to the accompanying drawing, forming a part thereof.

10 The drawing is a side elevation.

My design presents an upright column bifurcated at its upper portion and slightly widened at the extreme top, with a lateral extension L-wise at the foot. It also presents a 15 columnar structure of the body of the framing, with a bifurcated and widened top.

Referring to the drawing, A is the plain columnar portion of the framing, A' A² the

bifurcated portion, A³ A⁴ the widening at the extreme top, and A⁵ the L extension at the 20 bottom.

The forms and proportions may be varied within considerable limits, so long as the general effect is preserved.

I claim—

1. The design herein shown and described, consisting of the columnar framing A, bifurcated portion A' A², and widened top A³ A⁴. 25

2. The design for steam-engine frame herein shown and described, consisting of the 30 columnar framing A, bifurcated portion A' A², widened top A³ A⁴, and the L extension A⁵.

DAVID N. MELVIN.
